HENRIK OLSEN RØVIG, OF OSLO, NORWAY

MACHINE FOR CUTTING OFF BANDS

Application filed August 15, 1928, Serial No. 299,828, and in Norway February 7, 1928.

The present invention relates to a machine for cutting off bands in certain lengths, and the machine is also constructed in such a manner, that the lengths of the bands in an easy and convenient manner may be varied within certain limits.

The invention is shown in the accompanying drawing, in which:

Figure 1 is a front view of the machine.
10 Figure 2 is a side view of the same.
Figure 3 is a plan view of the same.

In the drawing —1— indicates a stand or a socle, which at one end has a bearing —2—, in which a friction plate —3— is rotatably mounted, which at the same time serves as a fly-wheel. At the other end of the socle two friction rollers —4— and —5— are rotatably mounted. The roller —4— is keyed on a shaft —6—, which extends towards the bearing —2— and is parallel with the plate —3—, so that the axis of the same crosses the axis of the plate —3—. The roller —5— ought to be mounted somewhat yielding in the vertical direction owing to the different thickness of the bands which the rollers are to convey. On the shaft —6— a friction wheel is arranged slidably but not rotatably, which wheel is in constant engagement with the friction plate —3—. The wheel —7— is mounted on the shaft —6— by means of an arm —8—, which is connected with the hub of the wheel —7—, so that this wheel may rotate relative to the arm, which is loosely placed on the shaft —6—. At the free end

35 the arm —8— has a head bolt —9—, which is in engagement with a slot —10— in the stand —1—, and which by a winged nut —11— may be fastened in such a manner, that the arm —8— with the wheel —7— is kept in the desired position on the shaft —6—. In connection with the arm —8— a scale —12— may be arranged on the stand, which indicates the lengths of the bands which are cut off. The cutting device itself

45 consists of a rotatable roller —13—, mounted on the plate —3—, which roller extends somewhat in front of the circumference of the plate. This roller co-acts with a knife —14—, which is pivotally mounted on the stand, and which by a spring —15— is kept in the nor-

mal position shown in the drawing, lying against a button —16— with the cutting edge lying directly above a slit —17—, through which the band arrives, conveyed by the rollers —4—5—. That part of the knife —14—, 55 which co-acts with the roller —13— is formed with a slanting surface —18—. In the performance shown in the drawing, which is adapted to be driven by hand, a handle —19— is fixed to the friction plate 60 —3—.

The machine operates in the following manner:

Suppose that a band is inserted between the rollers —4—5— and that the plate —3— 65 is rotated in the direction indicated by the arrow, then the wheel —7—, the shaft —6— and the rollers —4—5— will be made rotating and conveying the band a certain length for each revolution of the plate —3—. 70 Each time the roller —13— strikes against the slanting surface —18— of the knife —14—, the same will swing down round its pivot and cut off the band, conveyed through the slit —17— by the rollers —4—5—. After 75 the roller —13— has passed the knife, the same will again by the spring be brought back in its normal position, lying against the button —16—. It will be understood that by placing the friction wheel —7— at a smaller 80 or greater distance from the axis of rotation of the plate —3—, the lengths of the bands cut off will be shorter or longer.

The performance shown in the drawing is only given as an example, as alterations may 85 be made without departing from the scope of the invention. For instance the machine may be constructed to be driven mechanically and arranged in such a manner, that for each revolution of the disc more than one band 90 is cut off. By substituting the knife —14— with a counting apparatus, which is acted on by the roller —13— during the rotation of the disc —3—, the machine can also effectively 95 be used for measuring bands.

What I claim is:

1. In combination with feeding rolls of means for cutting the product delivered from said rolls in predetermined lengths, comprising a shaft connected to one of said rolls, a 100

friction driven disk for driving said shaft adapted to slide longitudinally with respect to said shaft, a rotatable friction driving disk disposed parallel to said shaft and adapted to frictionally engage said driven disk for driving said shaft, means for maintaining said driven disk in any desired position along a line on the friction disk parallel to said shaft, a shear for cutting the product, means 10 on said driving disk for mechanically actuating said cutting shear, and means for rotating said driving disk.

2. In combination with feeding rolls, of means for cutting the product delivered from 15 said rolls in predetermined lengths comprising a shaft connected to one of said rolls, a driven disk slidable longitudinally on said shaft and adapted to rotate said shaft, a rotatable friction driving disk disposed parallel 20 to said shaft and frictionally engaging said driven disk, means for maintaining said driven disk in any desired position along a line on the friction disk parallel to said shaft, a scale graduated to indicate the 25 lengths of the product severed, a shear for cutting the product, means on the circumference of said driving disk adapted to mechanically actuate said cutting shear, and means for rotating said driven disk.

30 In testimony whereof I have signed my name to this specification.

HENRIK OLSEN RØVIG.
